UNITED STATES PATENT OFFICE.

CHARLES ANDREWS, JR., OF ROCKFORD, ILLINOIS, ASSIGNOR TO THE
ANDREWS WIRE AND IRON WORKS, OF SAME PLACE.

DESIGN FOR AN EASEL.

SPECIFICATION forming part of Design No. 32,636, dated May 8, 1900.

Application filed April 10, 1900. Serial No. 12,383. Term of patent 7 years.

To all whom it may concern:

Be it known that I, CHARLES ANDREWS, Jr., a citizen of the United States, residing at Rockford, in the county of Winnebago and State of Illinois, have invented and produced a new and original Design for Easels, of which the following is a specification, reference being had to the accompanying drawing, forming part thereof, being an isometrical representation of the easel.

As shown in the drawing, my design consists in the formation of the easel having the front cross-bar 1, vertical loops 2, horizontal portions 3, raised projections 4, and coiled feet 5, bent from a single piece of wire.

Having described my invention, what I claim as new, and desire to secure by Letters Patent, is—

The design for an easel as herein shown and described.

In testimony whereof I have signed my name to this specification in the presence of two subscribing witnesses.

CHARLES ANDREWS, JR.
